FRANK E. HOUSH, OF WINTHROP, MASSACHUSETTS.

LOCKING-BINDER FOR BOOKS.

1,127,004.

Specification of Letters Patent.

Patented Feb. 2, 1915.

Application filed January 26, 1914. Serial No. 814,352.

To all whom it may concern:

Be it known that I, FRANK E. HOUSH, a citizen of the United States, residing at Winthrop, in the county of Suffolk and State of Massachusetts, have invented new and useful Improvements in Locking-Binders for Books, of which the following is a specification.

This invention relates to improvements 10 in locking binders for books.

Under modern systems of keeping records, in which loose leaf books are employed, it is desirable to have some convenient and effective means by which the removal of 15 leaves by unauthorized persons can be prevented. This is specially important, sometimes, for preventing the substitution of one leaf for another. It is also sometimes desired, both with such books, and with 20 books that are permanently bound, to be able to lock the book closed, so that no one but an authorized person can see the contents. Various devices have been proposed for this purpose, and all are subject to various 25 objections, either on account of the space required, or because they are not secure, owing to the simplicity of the method of unlocking, or because they are cumbersome, or for other reasons. It is the purpose 30 of the present invention to provide a book lock in which all of these objections are eliminated, and in which certain positive advantages are gained, such as the ability 35 of the lock to grow or shrink with the size of the book, as leaves are added or removed. These objects are attained by providing a 40 U-shaped pieces or straps, preferably metallic, which overlap each other within the book and whose external portions are locked together. Specifically the external portions 45 may overlap each other and be provided with holes that register together, through 50 which a bolt may pass. In the less expensive embodiments of the invention, the lock may be a padlock; and so the very wide range of locks and variety of keys that characterize locks of this type are rendered available. The lock may be wholly within the cover of the book, and so not exposed to view when it is applied to the back of the book, or it may be exposed to view, as when

applied to the front of the book. If applied 55 to the back, the padlock may rest normally in a recess formed in the back edge of the pack of leaves. In a somewhat better, though more expensive embodiment of the invention, the lock may fill the entire recess 60 in the back of the book. This allows more room for the lock, greater strength, and a still wider range of keys.

The invention may be applied in various ways, and with many modifications, the two 65 embodiments above mentioned being here shown as illustrating the principle and the means of applying it; so that the patent is not to be taken as limited to the specific 70 embodiments of the invention here illustrated, but may be embodied in forms that differ in various respects within the scope of the appended claims, it being the purpose of the patent to cover, in the appended 75 claims, whatever features of patentable novelty exist in the invention disclosed.

In the accompanying drawings, Figure 1 is a perspective of a book and lock embodying the invention, showing a lock applied in two places; Fig. 2 is a detail, in perspective, partly in section; Fig. 3 is a detail showing the same lock as in Fig. 2, holding the same book after it has been made thicker by the addition of leaves; Fig. 4 shows a modified form of the invention; and Fig. 5 shows a style of keeper that may be used.

Referring to the drawings, 10 represents the pack of sheets of paper, cardboard, or other material which constitute the leaves of a loose leaf book. It is customary in 90 loose leaf books that one or both flaps of the cover and the back of the cover be easily removable from the pack, in order that sheets may be removed or added; and the invention is illustrated as it may be applied 95 to such a book. The binding may be of any ordinary or suitable type, and accordingly the drawing shows a binding of one of the simplest types, where the leaves are penetrated by round holes through which tubes 100 11 and posts 12 pass, the tubes being screw threaded internally at their upper ends, and the posts being screw threaded throughout their length, so that they can be inserted to any depth, thus holding and clamping the 105 stubs of the sheets together. This device which binds the leaves together passes also through the cover of the book and so con-

stitutes the binding of the book, but the pack may if preferred be otherwise secured in position within the cover.

About in the middle of the stub or back margin, the pack is pierced by a hole 13, which in the case illustrated is long and narrow, extending up and down the sheet parallel to the back, at a short distance from the back edge of the pack. Preferably the hole 13 is at about the same distance from the back edge as are the holes through which the binding posts 11, 12 pass, so that, when a leaf is turned, its stub end will be held on a substantially straight line by the lock and by the binding posts. A recess 14 is formed in the back edge of the pack deep enough to contain the lock. Stiff metallic straps 15 are provided, having substantially a U-shape, the bowl of the U being preferably rectangular with respect to the sides. As represented in Figs. 2 and 3, these consist of three portions, *a*, *b*, *c*, in which the portion *a* is adapted to be inserted in the hole 13, the portion *b* to lie flat on the top of the uppermost sheet of the pack when portion *a* has been inserted to its limit, and the portion *c* to lie on the outside, parallel to and flat against the edge of the pack within the recess 14, but having a tab *d* formed integrally therewith and bent so that it stands out at right angles to the edge of the pack, though preferably wholly within the recess. Two of these pieces 15 are provided, identically alike, one being adapted to be inserted in the hole 13 from each side of the pack. When so inserted, the portions *a* of each will overlap each other within the hole 13; portions *c* will overlap each other on the exterior; and the portions *d* likewise overlap each other will come opposite each other so that the bolt or hook of a padlock 17 may be inserted through a hole 16 in one strap and through a hole 16 in the other strap. While these straps may be made in different ways, the drawings illustrate in Figs. 1, 2, and 3, a method which has special advantages in that the entire construction is simple, inexpensive, and strong, and may be either a simple binder or a locked binder.

The strap being flat, a portion *d* occupying about half of its width, extending for any desired length of the portion *c*, is bent outward so that it constitutes an out-turned lug through which one or more holes 16 may be provided. When a padlock is passed through a hole 16 in one strap, and a hole 16 in the other strap, these two straps cannot be separated far enough to cease to overlap; and consequently no leaf or sheet can escape.

The binder lock may be so designed as to operate between rather wide limits; and a book, made of a pack of sheets of a certain thickness as represented in Fig. 2, may be enlarged by addition of leaves to a considerably greater thickness, as indicated in Fig.

3, and still be held by the same lock, provided that suitably located holes 16 are made; or some other means, so that the two straps can be locked together while spread to different distances apart. To accommodate a greater enlargement, other straps having longer portions *a* and *c* may be substituted at small expense.

When the back of the cover of the book fits close to the back of the pack of sheets, it is desirable to provide space for the padlock by making a recess 14 in the back of the pack. This recess may be as large in area, and may be cut as deeply into the pack, as the size and shape of a suitable padlock will require, without materially affecting the strength, area of page, flexibility, size, or other qualities of the book. When thus applied, the book is locked against the removal of sheets, but the lock is not noticeable, and the book may be opened and used as freely as if the lock were not there. When applied to other edges of the pack, for example to the front edge, the lock will prevent the opening of the book. In such case, no recess is needed for receiving the padlock, and a fastening may be accomplished by providing a simple hole in the margin of the sheet. Such a hole, while always visible when the book is open, is not such as to interfere in any way with the use of the page, being so close to the edge; while the visibility of the lock when the book is closed does no harm.

It is not necessary that the outside portions of the strap should overlap each other, but any means fastening them together so as to prevent separation is sufficient; and so, for example, another method of holding them together is illustrated in Fig. 4. As there represented, the entire recess 14 is neatly filled by the casing of a lock 17', from which a strap 15' passes under the book and up into the hole 13, this strap being integral with, or otherwise firmly attached to, the body portion of the lock 17'. The other strap 15'' overlaps the strap 15' within the hole 13, and exteriorly thereof is capable of insertion into the lock 17', as illustrated, where it is engaged and held by the internal mechanism of the lock, which may be of any suitable kind. This contrivance, utilizing the entire space of the recess 14, both permits the use of a very strong construction of lock, and facilitates the use of a lock with several tumblers which may be controlled by a flat or corrugated key, as indicated by the key-hole 17''.

With some types of books, the recess 14 may be omitted even when the binder lock is placed on the back. In such a case, the lock will project somewhat from the back edge of the pack, but if the back of the cover be large and loose enough there may be no objection to this; or, if there be no cover, or

side covers without a back, bound together with the pack or sheets, as may be done in some grades of books used for commercial purposes, the lock may be allowed to project. It should be noted, however, that the recess 14 can ordinarily be made with no extra cost whatever, being cut at the same time and by the same operation that cuts holes for the binding; also that it avails itself of space that would not otherwise be utilized; and further that it can be made shallower, or with different shaped outer corners than the form illustrated. These facts, together with the flatness with which 15 the portions *b* of the straps lie against the sides of the pack of sheets, make the use of a recess desirable even for books which have no back cover.

It is further to be observed that the locking means is in itself a binder, in the sense that it holds the leaves of the pack together, as well as a lock, in the sense that it prevents an unauthorized person from removing them; and so in some cases it may be preferred to omit the binding means typified by the numerals 11, 12, and to substitute two or more sets of the binder straps of the invention; and, while in the most complete form of the invention a lock is used as above described to secure these two straps together externally, some other means that does not rise to the dignity of an actual lock, as for example a split ring 17", as illustrated in Fig. 5, may be employed to secure the straps 35 together. This provides a binding means that is equally as secure as ordinary binding means typified by the numbers 11, 12, and with which an actual lock may be used at pleasure.

40 I claim as my invention:

1. A combined book and lock therefor, comprising the combination of a book having a cover removable so as to expose the back edges of the leaves of the book, said 45 leaves being formed with a recess in their back edges adapted to receive a lock, and with a hole adjacent to the recess, penetrating the leaves transversely; with binder straps adapted to be inserted in said hole 50 from opposite directions, and to overlap

each other within the book; and said lock, fastening together the said straps externally.

2. A book lock comprising two flat sheet metal straps substantially similar in form, 55 and adapted to penetrate the pack of leaves transversely near its edge from opposite sides, and to overlap each other within the book; and lugs integral with said straps, outside the pack and turned outward therefrom, provided with holes; combined with a lock adapted to engage said lugs through said holes, thereby holding the straps in their overlapping relation within the pack.

3. A book comprising sheets and binding 65 means from which the sheets are removable, arranged in a substantially straight line at the back edge of the pack of sheets, combined with straps penetrating the sheets transversely at a position in substantially 70 the same line, and overlapping each other within the pack; and means for locking the external portion of said straps together on the back edge of the pack of sheets within the cover of the book.

75 4. The combination of a pack of sheets having a recess formed in its edge and a hole adjacent to the edge, both recess and hole extending transversely of the pack, with two binder straps adapted to be inserted 80 from opposite directions into the hole to overlap each other therein, and into the recess to be fastened to each other therein.

5. The combination of a pack of sheets having a hole adjacent to the edge, extending 85 transversely of the pack, with two binder straps adapted to be inserted from opposite directions into the hole, to overlap each other therein, and adapted to overlap and be fastened to each other externally, 90 there being on said external overlapping portions means for fastening at a multiplicity of different distances of overlapping, whereby the binding is extensible.

Signed by me at Boston, Mass., this 95 twenty-second day of January, 1914.
